Attorney

UNITED STATES PATENT OFFICE.

DAVID W. OLINGER, OF MILTON, OREGON.

PICK-UP DRUM.

Application filed August 23, 1927. Serial No. 214,919.

This invention relates to a pick up drum and has relation more particularly to a device of this kind especially designed and adapted for use within a tank for washing 5 apples and the like, and it is an object of the invention to provide a drum of this kind which will operate to effect the desired lifting action without bruising the apples or the like.

Another object of the invention is to provide a drum of this kind which is substantially acidproof thereby materially prolonging the life of the drum.

My improved drum is particularly adapted 15 for use in connection with a tank employed for washing apples or the like for the removal from the fruit of the arsenate of lead spray.

The invention consists in the details of 20 construction and in the combination and arrangement of the several parts of my improved pick up drum whereby certain important advantages are attained and the device rendered simpler, less expensive and 25 otherwise more convenient and advantageous for use, as will be hereinafter more fully set forth.

The novel features of my invention will 30 hereinafter be definitely claimed.

In order that my invention may be the 35 better understood, I will now proceed to describe the same with reference to the accompanying drawing, wherein:—

Figure 1 is a view in elevation of a pick 40 up drum constructed in accordance with an embodiment of my invention;

Figure 2 is a sectional view taken substantially on the line 2—2 of Figure 1;

Figure 3 is a view in end elevation of the 45 drum as illustrated in Figure 1;

Figure 4 is a view in perspective of one 50 of the fingers herein employed in disassembled relation.

As herein disclosed, my improved drum 55 comprises a core 1 of desired length and preferably made of wood, said core 1 being substantially square in cross section. To the ends of the core 1 are suitably affixed the discs 2, said discs being of a diameter greater than the maximum diameter of the core 1 with said core arranged at the central portions of the discs. The discs 2 are also preferably made of wood and the drum is of a length and the discs 2 of such thickness to 60 snugly fit within a tank of desired width.

The core 1 has fitted in its opposite ends

at axial centers thereof the pins 3, also preferably of wood, projecting a desired distance outwardly of the discs 2 whereby the drum may be rotatably supported by opposed walls of an acid tank. One or both of the pins 3 is adapted to have operatively engaged therewith a suitable driving medium (not shown), preferably a belt or chain leading from a suitable source of power. 65

Each of the faces *a* of the core 1 has disposed transversely thereof and suitably secured thereto a series of fingers 4, said fingers being spaced in a direction lengthwise of the core 1 with adjacent fingers in relatively close proximity to the others. These fingers 4 project beyond an adjacent face of the core 1 and said extended portion of each of the fingers 4 has its outer edge disposed on an outward curvature, as at *b*, whereby 70 the extended portion of each of the fingers 4 is gradually increased in width with the inner edge of said extended portion straight. 75

Each of the fingers 4 is provided with a rubber facing 5 and the outer end of each series of fingers 4 has secured thereto a pick up strip 6 of rubber or a rubber faced bar. This strip 6 extends lengthwise of the core 1 and has its extremities suitably secured to the peripheral edges of the discs 2. 80 85

It is to be particularly noted that each series of fingers 4 is disposed in the same general direction.

A pick up drum constructed as hereinbefore described can be produced with economy and in view of the fact that the fingers 4 are provided with rubber facings as also the strips 6, these parts are rendered acidproof thus materially prolonging the life 90 of the drum. 95

My improved drum is adapted to be mounted upon the upper portion of the discharge end of a tank or vat in which fruit, such as apples, or the like, are adapted to be washed. As the drum rotates the projected portions of the fingers 4 extend below the liquid level within the tank or vat. The direction of rotation of the drum is such as to bring the straight edges of the extended portions of the fingers 4 upwardly beneath the fruit or the like floating upon the solution within the tank or vat, said fruit or the like being held against displacement upon said extended portions by the strips 6. As a series of fingers 4 pass upwardly with its 100 load such load is transferred to the fingers 4 105 in advance thereof and the fruit is then dis- 110

charged over the curved edges *b* into a basket or other container properly positioned exteriorly of the tank or vat. The curved portions *b* serve to retard the speed of travel of 5 the fruit or the like so that the liability of bruising or marring of the fruit is materially reduced. This washing action of the fruit is to remove therefrom the arsenate of lead spray applied to the fruit during its 10 development and it has been found in practice that with a drum such as hereinbefore set forth five feet in length or fitted within a tank five feet in width, two boxes of fruit, such as apples, will be washed with the drum 15 rotating at a speed of from four and a half to five R. P. M.

From the foregoing description it is thought to be obvious that a pick up drum constructed in accordance with my invention 20 is particularly well adapted for use by reason of the convenience and facility with which it may be assembled and operated, and it will also be obvious that my invention is susceptible of some change and modification 25 without departing from the principles and spirit thereof and for this reason I do not wish to be understood as limiting myself to the precise arrangement and formation of the several parts herein shown in carrying 30 out my invention in practice except as hereinafter claimed.

I claim:—

1. A pick up drum comprising a core, a 35 plurality of series of fingers carried by the core and disposed in the same general direction, each series of fingers being spaced lengthwise of the core and projecting therebeyond, and a pick up strip carried by the outer extremities of each series of fingers, 40 the fingers of each series being angularly disposed with respect to the fingers in the adjacent series, the fingers of one series discharging the load collected thereupon during the rotation of the drum upon the fingers

of the series immediately in advance thereof. 45

2. A pick up drum comprising a core, a plurality of series of fingers carried by the core and disposed in the same general direction, each series of fingers being spaced lengthwise of the core and projecting therebeyond, a pick up strip carried by the outer extremities of each series of fingers, and discs carried by the ends of the core, the pick up strips being secured to the peripheral edges of the discs. 55

3. A pick up drum comprising a core, a plurality of series of fingers carried by the core and disposed in the same general direction, each series of fingers being spaced lengthwise of the core and projecting therebeyond, and a pick up strip carried by the outer extremities of each series of fingers, each of said pick up strips being rubber faced. 60

4. A pick up drum comprising a core, a 65 plurality of series of fingers carried by the core and disposed in the same general direction, each series of fingers being spaced lengthwise of the core and projecting therebeyond, and a pick up strip carried by the outer extremities of each series of fingers, 70 said core being angular in cross section to provide a plurality of flat faces, each series of fingers being disposed transversely across one of said flat faces. 75

5. A pick up drum comprising a core, a plurality of series of fingers carried by the core and disposed in the same general direction, each series of fingers being spaced lengthwise of the core and projecting therebeyond, and a pick up strip carried by the outer extremities of each series of fingers, the 80 extended portion of each of the fingers being increased in width from the core to the outer end thereof. 85

In testimony whereof I hereunto affix my signature.

DAVID W. OLINGER.
